(57) CLAIM

(21) Appl. No.: **29/183,179**

The ornamental design for an illuminating apparatus for liquid crystal display device, as shown and described.

(22) Filed: **Jun. 9, 2003**

DESCRIPTION

Related U.S. Application Data

(62) Division of application No. 29/153,608, filed on Jan. 14, 2002.

The article according to the design is incorporated in a portable telephone, a portable terminal for information device, etc. so as to illuminate a liquid crystal display from the front side.

(30) **Foreign Application Priority Data**

Jul. 18, 2001 (JP) 2001-020999
 Jul. 18, 2001 (JP) 2001-021000

 Jul. 18, 2001 (JP) 2001-021003

Light emitted from the light source, traveling through a light conductive member and a light diffusing plate and introduced into a light conductive plate uniformly illuminates the whole surface of the liquid crystal display thanks to micro-prisms formed on the surface of the light conductive plate. A transparent cover is provided over the exposed surface of the article incorporated in the portable telephone, etc. so as to protect the micro-prisms from dust, dirt, scratches, etc.

(51) **LOC (7) Cl.** **14-02**
 (52) **U.S. Cl.** **D14/448; D26/1**

FIG. 1 is a front view of an illuminating apparatus for liquid crystal display device showing our new design;
 FIG. 2 is a top plan view thereof;
